CYRIL BAGULEY, OF HANWORTH, ENGLAND

PROP FOR USE IN MINES

Application filed May 7, 1930, Serial No. 450,497, and in Great Britain May 10, 1929.

This invention relates to an improved prop for use in mines or other places for supporting the roof or other purposes.

The object of this invention is to provide a simple, cheap and effective form of prop which will be substantially rigid in use and capable of withstanding great pressure but which may be readily collapsed at will in order to enable it to be easily withdrawn and 10 may then be re-erected for use again as often as desired.

According to my invention the body of a pit prop or the like is composed of parts 15 slideable axially relative to one another and having interposed between them means for moving them apart and for bringing them towards each other.

In carrying my invention into practice it is preferred to employ a length of steel or 20 other suitable tubing of a size and thickness sufficient to support the load to which the prop is likely to be subjected. At the top of the tube is provided a head-piece to engage with the roof or other part. This may be 25 enlarged on its upper surface at the point of contact with the mine roof or the like, or the wooden bearer which is usually interposed between them. A corresponding foot-piece is provided at the lower end of the steel tube.

30 The head-piece and foot-piece may conveniently be formed as malleable castings of iron or as drop forgings or in any other convenient manner. A suitable spigot is provided both on the head-piece and the foot-piece to 35 engage in the respective ends of the steel tube which is thus effectively located between them. Alternately the tube ends may engage in a recess in the head and foot piece respectively. The engaging surfaces of the head 40 piece and foot piece with the steel tube are suitably shaped so that relative movement between them will tend to increase the length of the prop by forcing the head piece and foot piece apart. For this purpose the en-

45 gaging surfaces may be of wedge shape and may consist of any suitable number of teeth or wedge like projections on one member which engage with corresponding inclined surfaces on the other member.

50 In the simplest and preferred construction

the top and bottom ends of the steel tube are provided with a suitable number of teeth or wedge shaped projections inclined in opposite directions to each other. Corresponding teeth or wedge shaped projections are formed 55 on the head piece and the foot piece respectively. Means is provided to enable the tubular portion of the prop to be rotated relatively to the head piece or the foot piece or both for the purpose of expanding and contracting the prop by forcing apart or releasing the head piece and foot piece. For this purpose one or more apertures may be formed in the tubular strut at suitable positions to enable it to be rotated so that its 60 shaped ends will effect a wedging action 65 against the corresponding teeth or inclined plane on the head piece or foot piece. If desired the tube may be thickened or increased in strength at the position where such 70 holes are made so that the effective strength of the prop may not be reduced. Other means may be employed for rotating the prop such 75 for instance as a pipe grip or wrench thus obviating the necessity of cutting the tube or otherwise reducing its strength. As a further alternative suitable portions of the prop may be expanded or shaped to an hexagonal or other suitable form to enable a spanner or wrench to be applied for the purpose of rotating the tubular portion of the prop. 80

Suitable means may be employed to lock the parts in the expanded position. One suitable method of doing this consists in forming 85 a series of apertures in the spigot of the head piece or foot piece or both and providing a pin adapted to be passed through a corresponding aperture in the tubular portion of the prop near its end or ends. By carefully 90 calculating the angle of the inclined wedge-shaped members these may be so designed that the parts will remain effectively locked in the position to which they are removed to expand the prop without the necessity for 95 employing any separate locking mechanism.

If desired the ends of the tubular portion of the prop may be "jumped up" or otherwise increased in thickness or cross section to provide an additional bearing surface for the 100

wedge-shaped members which engage with the foot piece and head piece respectively.

The head piece and the foot piece may be suitably shaped or formed on their upper and lower surfaces respectively to engage against the wooden backing, and so engaged against the wooden backing as to prevent relative rotation between them. For this purpose the surfaces may be serrated or provided with projections or teeth which will become embedded in the wooden backing. The head piece and foot piece may be conveniently connected together by suitable links, chains, wire or other flexible connections extending between the two portions and preferably located within the tubular portion of the prop. This will prevent the parts from becoming dislodged when the prop is removed and when it is being conveyed from place to place.

In order that my invention may be clearly understood and readily carried into effect I have appended hereto a sheet of drawings illustrating embodiments thereof, and wherein:

Fig. 1 is a broken elevation view showing the prop in its contracted condition.

Fig. 2 is a broken elevation view showing the outer parts of the prop separated from each other.

Fig. 3 is a broken sectional elevation view of Fig. 1.

Fig. 4 is a sectional plan view.

Fig. 5 is a broken detail sectional elevation view showing a slight modification of the method of resiliently connecting the upper and lower parts of the prop.

Fig. 6 is a detail view showing in side elevation a modified prop expanding and contracting member in the blank, and

Fig. 7 shows such member bent to tubular form.

Referring to the drawings, the embodiment illustrated is suitable for the normal requirements of mine pit props and consists of two metal tubes *a* and *b* between the opposing ends of which is located a metal tube or ring *c* adapted to be operated to increase the effective length of the prop.

The members *a* and *b* are preferably composed of steel and are formed with flared or otherwise suitably shaped lower and upper ends *d* and *e* respectively adapted to engage bearers *f*, and if desired these bearers may be attached to the prop. These prop ends *d* and *e* can be formed with teeth or spikes to obtain a bite in the bearers or other surfaces engaged by them, and if desired such ends may be flanged outwards.

The upper and lower ends respectively of the tubular members *a* and *b* are also preferably enlarged in thickness or flared externally as indicated at *a*¹ and *b*¹ to provide ample support for the ring *c* and to enable the major portion of the prop to be of convenient diameter for handling. The members *a*, *b*

and *c* are held in axial alignment by a spigot or tube *g* fitted concentrically within them, and threaded, riveted, welded or formed integral with any one of the parts *a*, *b* and *c*, or resting on a ledge or other suitable support in the member *a* or otherwise held in a position which ensures the parts *a*, *b* and *c* being held in axial alignment but yet permitting the member *c* to be rotated relative to the parts *a* and *b*.

The annular edges of the member *c* are formed with symmetrical elongated arcuate ratchet like teeth or cams *h*, and the opposing edges of the members *a* and *b* are correspondingly shaped with recesses *i* to receive the cams *h*. By this means when the cams *h* are fully accommodated in the recesses *i* the proper continuity and solidarity of the prop is effected, but by rotating the ring *c* relative to the members *a* and *b* the part *b* is raised from the part *a* and thereby the prop becomes effectively wedged between roof and floor or between walls. The pitch of the cam like teeth *h* and the corresponding recesses *i* is such that under normal or excessive pressures the ring *c* will be firmly held in any position it may be turned to about the axis of the prop.

Any suitable means may be provided for turning the ring *c*. For instance the external surface of the ring can be shaped to receive a spanner, or when it is integral with the tube *g* it can have tommy bar holes through it. As an example I have shown a number of short radial lugs *j* extending from the ring *c* and apertured to receive suitable tools, or adapted to provide abutments for a spanner. The ring *c* may be bent from a straight blank as shown in Fig. 6 for example to a ring as shown in Fig. 7, the ends of the blank being bent to provide a pair of lugs *k* through which a bolt or rivet is passed. If desired this arrangement can be utilized as a means of holding the ring *c* in selected position, by adapting it as a split collar about the tube *g* and clamping it to the sleeve by adjusting the nut on the bolt passed through the lugs *k*. The lugs *k* provide a projection for striking the ring when it is desired to rotate it to contract the prop, or extend it.

If desired the ring *c* may be located nearer the base of the prop than the top, or midway. Also if desired two or more rings *c* and correspondingly divided parts of the prop may be employed with each prop. In practice it may be found desirable to cover or shroud the rotary ring to prevent possibility of fingers being trapped. A suitable stop or stops may be provided to limit the rotary movement of the ring *c* and the stop or stops may be so arranged as to prevent movement beyond a position at which there is a sufficient length of contact between the wedge shaped faces to efficiently support the load without subjecting the material to too great pressure per square inch.

In order to normally maintain the parts of the prop connected and yet permit extension and contraction of the prop the parts *a* and *b* can be resiliently connected, for instance by a stay rod, chain or cable *l* anchored by an eye bolt *m* or other suitable means to a plate or flange *n* in one end of the prop, and to an eye bolt *o* secured in like manner to the other end of the prop, one or both of these eye bolts having a compression spring *p* interposed between its nut *q* and the appropriate plate or flange *n*. As an alternative or additional form of resilient connection the ligature *l* can contain a coiled tension spring *r* as shown in Fig. 5.

If desired only one annular edge of the ring *c* can be provided with the cam like teeth *h* the other edge and the opposing end of the appropriate part of the prop being flat horizontally.

My improved prop may be cheaply constructed in a form which may be easily applied in mines for supporting the roof or for other purposes and may be arranged to carry very great loads without the risk of collapse. The prop however may be readily released and withdrawn when desired and when removed may be conveyed to other parts and used again as often as required.

I claim:

1. A pit prop comprising two tubular coaxial body parts, a relatively rotatable tubular member interposed between them, means connecting the two parts and said member against lateral displacement, cam like surfaces on the ends of said interposed member and corresponding surfaces on the opposing ends of the said two body parts, said interposed member being rotatable about the axis of the prop.

2. A pit prop comprising two tubular coaxial body parts, a relatively rotatable tubular member interposed between them, a concentric spigot fitted inside the said two parts and said member to hold them against relative lateral displacement, cam like surfaces on the ends of said interposed member and corresponding surfaces on the opposing ends of the said two body parts, said interposed member being rotatable about the axis of the prop.

3. A pit prop comprising two tubular coaxial body parts, a relatively rotatable tubular member interposed between them, means connecting the two parts and said member against lateral displacement, cam like surfaces on the ends of said interposed member and corresponding surfaces on the opposing ends of the said two body parts, said interposed member being rotatable about the axis of the prop, and spring means inside the prop connected to said two body parts so as to press them against said interposed member.

4. A pit prop comprising two tubular coaxial body parts, a relatively rotatable tubu-

lar member interposed between them, means connecting the two parts and said member against lateral displacement, cam like surfaces on the ends of said interposed member and corresponding surfaces on the opposing ends of the said two body parts, said interposed member being rotatable about the axis of the prop, abutments in said body parts, a ligature connected to said abutments and a spring placing said ligature under tension.

5. A pit prop comprising two tubular coaxial body parts, a relatively rotatable tubular member interposed between them, means connecting the two parts and said member against lateral displacement, cam like surfaces on the ends of said interposed member and corresponding surfaces on the opposing ends of the said two body parts, said interposed member being rotatable about the axis of the prop, abutments in said body parts, a ligature connected to said abutments and a spring placing said ligature under tension, said spring means having associated with it means for adjusting said tension.

6. A pit prop comprising two tubular coaxial body parts, a relatively rotatable tubular member interposed between them, means connecting the two parts and said member against lateral displacement, cam like surfaces on the ends of said interposed member and corresponding surfaces on the opposing ends of the said two body parts, said interposed member being rotatable about the axis of the prop, abutments in said body parts, a ligature connected to said abutments and a spring placing said ligature under tension, and said interposed member being formed with means whereby it can be rotated with the aid of a tool.

7. In a pit prop a pair of coaxially aligned prop body parts, a relatively rotatable coaxial member between them against which member the pair of prop body parts are adapted to press in opposite directions, and a set of cam like projections on said intermediate member and on one of said prop body parts seating against each other whereby rotation of said intermediate member will effect axial separation of the two prop body parts.
